(57) **CLAIM**

The ornamental design for a housing for fiber sub-system, as shown and described.

DESCRIPTION

FIG. 1 is a front perspective view of a housing incorporating a design according to the invention.

FIG. 2 is a front view of the housing of FIG. 1.

FIG. 3 is a back view of the housing of FIG. 1.

FIG. 4 is a right side view of the housing of FIG. 1.

FIG. 5 is a left side view of the housing of FIG. 1.

FIG. 6 is a top view of the housing of FIG. 1; and,

FIG. 7 is a bottom view of the housing of FIG. 1.

The broken lines showing separators are included for illustration purposes only and form no part of the claimed design.

1 Claim, 5 Drawing Sheets
